UNITED STATES PATENT OFFICE.

FREDERICK LE ROY-TRACY, OF SYDNEY, NEW SOUTH WALES, AUSTRALIA.

BINDING PLATE FOR OFFICE LETTER FILES AND THE LIKE.

Application filed March 26, 1919. Serial No. 285,395.

To all whom it may concern:

Be it known that I, FREDERICK LE ROY-TRACY, a subject of the King of Great Britain and Ireland, residing at Sydney, in the 5 State of New South Wales, Commonwealth of Australia, have invented certain new and useful Improvements in Binding Plates for Office Letter Files and the like, of which the following is a specification.

10 My invention relates to letter files of the type in which a flexible metal ribbon is used, and refers particularly to the binding plate used with loose leaf files of this class.

15 The object of the invention is to provide an improved binding plate which is adapted by a simple manipulation to lock the free ends of the flexible filing ribbon when in the turned down position.

20 The present invention consists in an improved article of manufacture comprising in combination an elongated binding plate apertured between the ends, a pair of raised tongues or clips towards each end in staggered relation and facing inwards, and metallic tape-ends, each adapted to be threaded through one of the said apertures and each adapted to be firmly engaged at both sides by the corresponding pair of clips, in order 25 to securely lock the tape ends in position.

But in order that the invention may be clearly understood reference will now be made to the drawings which accompany and form part of this complete specification 30 and in which:

Figure 1 is a small perspective view showing the invention applied to a letter file of the type herein referred to.

Figure 2 is an enlarged plan of the improved binding plate which forms the subject of this invention.

Figure 3 is an enlarged section through line *a*—*b* Figure 1 showing the binding plate in the unlocked position on the file.

45 Figure 4 is a plan of Figure 3.

Figure 5 is a plan showing the flexible points of the file bent down and locked to the binding plate.

In the drawings an ordinary portfolio 50 letter file is illustrated for the purpose of ascertaining the invention but it is to be understood that the improved binding plate

can be applied to any design of file of the type hereinbefore referred to.

The flexible ribbon 6 is threaded through 55 the base 7 of the portfolio file and bent upwards to form the filing points 8 on which the letters or other loose sheets 9 are filed.

The binding plate 10 which forms the subject of this invention consists of a long 60 narrow strip of sheet metal having two preferably rectangular apertures 11 positioned

so as to register with and permit the file points 8 to pass therethrough when in the raised position as shown in Figures 3 and 65

4. Between the ends of the plate 10 and each of the apertures 11 small tongues or clips 12 and 13 are cut and raised clear 70 of the plate surface. The bases of the two tongues 12 are in alignment with each other 75

and with corresponding sides of the apertures 11 while the bases of the tongues 13 are in alignment with the opposite sides of the apertures 11, thus the bases of tongues 75

12 and 13 are in staggered positions and 80 the tongues point in opposite directions. When the flexible file points 8 are turned down over the binding plate they can be firmly locked in position by placing them under the tongues 12 and 13 as shown in Figure 5.

When it is desired to release the file points from the binding plate their extreme ends are pushed outwards clear of the tongues 13, then raised and drawn inwards clear of 85 the tongues 12.

I claim:

A binding device comprising a backing having a pair of flexible prongs extending therefrom and adapted to pass through the 90

papers to be bound, a plate having a pair of apertures provided with parallel side walls, the side walls of one aperture being arranged in alignment with the side walls of the other aperture and said prongs extending through said apertures, a tongue arranged between one of said apertures and one end of the plate and including a vertical wall in alignment with one of the walls of the last mentioned aperture and a horizontal portion extending toward one edge 95

100 of the plate, and a second tongue arranged between the first mentioned tongue and one end of said plate and having a vertical wall

in alignment with the opposite wall of the last mentioned aperture, said second tongue also having a horizontal portion extending in a direction opposite to the horizontal portion of the first mentioned tongue, one of said prongs extending between the horizontal portions of said tongues and said plate and being engaged on opposite sides at

spaced points by the vertical portions of said tongues.

In testimony whereof he has affixed his signature in presence of two witnesses.

FREDERICK LE ROY-TRACY.

Witnesses:

T. C. ALLEN,
H. C. CAMPBELL.
